US0D1063193S

(12) **United States Design Patent** (10) **Patent No.:** **US D1,063,193 S**
(45) **Date of Patent:** ** *Feb. 18, 2025

(54) **COSMETIC APPLICATOR**

(71) Applicant: **Guangzhou Fanjiao Cosmetics Co., Ltd.**, Guangzhou (CN)

(72) Inventor: **Lifen Huang**, Guangzhou (CN)

(73) Assignee: **Guangzhou Fanjiao Cosmetics Co., Ltd.**, Guangzhou (CN)

(*) Notice: This patent is subject to a terminal disclaimer.

(**) Term: **15 Years**

(21) Appl. No.: **29/843,236**

(22) Filed: **Jun. 20, 2022**

(51) LOC (15) Cl. **28-02**

(52) U.S. Cl.

(57) **CLAIM**

The ornamental design for a cosmetic applicator, as shown and described.

DESCRIPTION

FIG. 1 is a perspective view of a cosmetic applicator showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines shown in the drawings depict portions of the cosmetic applicator that form no part of the claimed design.
